UNITED STATES PATENT OFFICE.

WILLIAM T. DONNELLY, OF NEW YORK, N. Y.

AUTOMATIC DRAINAGE-VALVE FOR AIR AND WATER.

SPECIFICATION forming part of Letters Patent No. 779,772, dated January 10, 1905.

Application filed October 8, 1904. Serial No. 227,744.

To all whom it may concern:

Be it known that I, WILLIAM T. DONNELLY, a citizen of the United States of America, residing in the borough of Brooklyn, city of New York, county of Kings, and State of New York, have invented certain new and useful Improvements in Automatic Drainage-Valves for Air and Water, of which the following is a specification.

10 My invention relates to improvements in automatic valves for regulating the discharge of air and of water of condensation from radiating devices, its object being to so construct the valve as to keep the valve-piece on its seat under ordinary conditions, while unseating the valve only during abnormal conditions, such as an unusually large condensation or accumulation of dirt. The frequent unseating of the valve will thus be avoided and a 20 longer life of the valve obtained.

For this purpose my invention consists, essentially, in an automatic valve comprising a valve body or casing provided with an inlet and an outlet, a main valve-piece normally resting upon its seat and adapted to control the outflow, a by-pass from the chamber above the valve-seat to the outlet-passage beneath the valve-seat, a pressure-motor provided with small vents and controlling said main 25 valve-piece, a normally closed larger vent through the stem connecting the valve-piece and the motor and establishing communication from the low-pressure space beneath the main valve to the space above the pressure-motor, an auxiliary valve-piece to control this 30 larger vent, and means to control said auxiliary valve-piece.

The nature of my invention will best be understood when described in connection with 40 the accompanying drawings, in which --

Figure 1 is a sectional elevation of my valve. Fig. 2 is a sectional elevation of part of my valve, showing a modification. Fig. 3 is a diagrammatic view illustrating the application of my valve to a steam-heating apparatus.

Similar letters of reference refer to corresponding parts throughout the several views.

Referring now to Fig. 3, A designates the steam-supply pipe of a heating apparatus; B, 50 ordinary valve controlling the supply of steam

to radiating devices C. At the outlet of the radiating devices is placed the valve D, which forms the subject of the present invention. The outlets from these valves lead to the returns E, feeding into a header F, connected 55 to the exhausting apparatus G.

The valve D consists of a valve-body e, Fig. 2, provided with the usual inlet a and outlet b, with a valve passage-way c, controlled by the valve-piece f, and provided with a 60 by-pass g large enough to remove the normal condensation. The valve-body is also provided with a screw-cap d to enable the operating mechanism to be placed in the valve-body. The operating mechanism consists, es- 65 sentially, of a pressure-motor h in the example shown, a movable piston, a main valve-piece f, connected to the motor h by a hollow stem i and adapted to control the passage-way c, a float j in the valve-chamber m, carrying rods n, passing through small vents o in the motor, to which rods is fastened an auxiliary valve-piece k, controlled by the float j and adapted to close the vent through the 70 rod i.

The motor is directly actuated by the difference in pressure upon its two sides, the pressure on the lower side or chamber m being that in the inlet-pipe a and the pressure on the upper side or in the chamber n during the operation of the valve being substantially that in the outlet-pipe b. During the period the valve is inactive the pressure on both sides of the motor is the same, being kept so by the small vents o in the pressure-motor. During 85 the period of action of the valve the upper chamber n is in communication with the outlet-pipe b through the hollow stem i, whose area is much greater than the effective area of the vents o, although for sake of clearly 90 showing the annular openings o the latter are shown enlarged on the drawings. A difference of pressure is thus produced on the motor sufficient to operate it. When the water accumulates in the chamber m to an extent 95 sufficient to raise the float j, and thereby the auxiliary valve-piece k, communication is afforded between the upper chamber n and the outlet b, thus reducing the pressure in the chamber n and causing the motor to act. 100

When the motor *h* moves upward, it lifts the main valve-piece *f* off its seat and allows the accumulated water to be blown out. Should the accumulation of water in the chamber *m* be due to the choking of the by-pass *g* with dirt, the same action will take place and the water and dirt blown out when the main valve-piece *f* is unseated. In order to make the action more positive, a supplementary valve-piece *l*, Fig. 2, may be added. This valve-piece consists of a washer fitted about the hollow stem *i* and about the two rods *p* and attached to or resting normally upon the shoulders *q* of the float *j*. A greater pressure is thus brought to bear upon the motor, as not only the vent in the rod *i* is open when the float rises, but the area of the small vents *o* in the piston is also considerably reduced by the washer *l* being held against the motor *h*. When the water has receded sufficiently, the float *j* will drop and the shoulders *r* on the rods *p* will hit the washer and remove it from the motor. The auxiliary valve-piece is then again in its normal position, closing the communication through the hollow stem *i*, the intercommunication between the upper and lower chambers reestablished, and the main valve-piece returned to its seat by the motor.

What I claim, and desire to secure by Letters Patent, is—

1. An automatic valve of the character specified comprising a valve body or casing forming a chamber provided with an inlet and an outlet, a main valve-piece normally resting upon its seat and adapted to control the outflow, a by-pass from the chamber above the valve-piece to the outlet, a pressure-motor provided with small vents and controlling said main valve-piece, a normally closed larger vent establishing communication between the low-pressure space beneath the main valve-seat and the space above the motor, an auxiliary valve-piece to control said larger vent and means for actuating said auxiliary valve-piece.

2. An automatic valve of the character specified comprising a valve body or casing forming a chamber provided with an inlet and an outlet, a main valve-piece normally resting upon its seat and adapted to control the outflow, a by-pass from the chamber above the valve-seat to the outlet, a pressure-motor comprising a piston placed within a cylindrical part of the casing and dividing the casing into a valve-chamber and an upper space, said motor being adapted to control said main valve-piece and provided with small vents between the valve-chamber and the upper space, a normally closed larger vent establishing communication between the low-pressure space beneath the main valve-seat and the upper space above the motor, an auxiliary valve-piece to

control said larger vent and means for actuating said auxiliary valve-piece.

3. An automatic valve of the character specified comprising a valve body or casing forming a chamber provided with an inlet and an outlet, a valve-opening between the inlet and the outlet, a main valve-piece adapted to control the passage through the valve-opening and normally resting upon its seat, a by-pass from the chamber above the valve-opening to the outlet large enough to remove the normal condensation, a pressure-motor separating the valve-chamber from the space above and adapted to control said main valve-piece, a hollow stem connecting the main valve-piece and the motor, its bore establishing communication between the outlet and the space above motor, an auxiliary valve-piece normally closing the upper end of the bore of said stem, a float within the valve-chamber actuating said auxiliary valve-piece and vents through the pressure-motor of considerably smaller aggregate area than the bore of the said valve-stem.

4. An automatic valve of the character specified comprising a valve body or casing forming a chamber provided with an inlet and an outlet, a main valve-piece adapted to control said outlet and normally closed, a by-pass from the chamber above the main valve-seat to the outlet, a pressure-motor provided with comparatively small vents and controlling said valve-piece, a normally closed larger vent through the said pressure-motor and the main valve-piece, an auxiliary valve-piece to control the said larger vent, and a supplementary valve-piece adapted to decrease the area of said smaller vents.

5. An automatic valve of the character specified comprising a valve body or casing forming a chamber provided with an inlet and an outlet, a main valve-piece adapted to control said outlet and normally closed, a by-pass from the chamber above the main valve-seat to the outlet, a pressure-motor provided with comparatively small vents and controlling said valve-piece, a normally closed larger vent through the said pressure-motor and the main valve-piece, an auxiliary valve-piece to control the said larger vent, a float to control said auxiliary valve-piece, and a supplementary valve-piece comprising a washer carried by said float and adapted to decrease the area of said smaller vents.

In testimony whereof I have signed my name to this specification, in the presence of two subscribing witnesses, this 7th day of October, 1904.

WILLIAM T. DONNELLY.
